CLAIM

The ornamental design for a display screen with transitional graphical user interface, as shown and described.

DESCRIPTION

FIG. 1 is a first image in a sequence for a display screen with transitional graphical user interface showing the new design;

FIG. 2 is the second image thereof;

FIG. 3 is the third image thereof;

FIG. 4 is the fourth image thereof; and,

FIG. 5 is the fifth image thereof.

The appearance of the display screen with transitional graphical user interface sequentially transitions between the images shown in FIGS. 1-5. The process or period in which one image transitions to another forms no part of the claimed design.

The dashed line English characters form no part of the claimed design. The outermost broken line illustrates a display screen and forms no part of the claimed design.
